UNITED STATES PATENT OFFICE

2,612,409

BRUSH-MAKING MACHINE

Ernst Aberle, Lillehammer, Norway

Application August 20, 1947, Serial No. 769,561
In Norway August 21, 1946

3 Claims. (Cl. 300—3)

1

The present invention relates to brush-making machines of the type comprising devices for the drilling of holes in the brush stocks, for the forming of bristle tufts and of staples and for the locating and securing of the bristles in the holes drilled in the stock, and it is the object of the invention to provide such arrangements that a greater production capacity may be obtained at the same time enabling the mechanical and simple production of brushes of such high quality and having such thin tufts which could previously only be manufactured by hand.

According to the invention this is accomplished thereby that the various devices mentioned above are pivotably mounted about a common axis, whereby all operations may be performed in the same position of the brush stock, the devices being combined in a tool head which is pivotably mounted about an axis. Thus by means of this arrangement it is possible automatically or semi-automatically to make a brush merely by bringing the brush stock mechanically or manually against or away from the tool head, thereby moving and, if desired, turning the brush stock in accordance with the distance and angle desired between the individual tufts. At the same time the tendency to inaccuracy and the complexity of machinery consequent to the previously usual method, wherein separate tools have been used and the brush stock has had to be moved or shifted from tool to tool or between operation stations are avoided.

The invention may be embodied in an automatic or semi-automatic machine so that the turning movement of the tool head and the reciprocating movement of the brush stock holder to and from the tool head are controlled by means of a common cam or curve disc, whereby an absolute synchronism is obtained as between the separate movements. The control of the other movements of the stock holder in the interval between the forming of the individual tufts may be accomplished in any manner for instance by means of a template.

It is also convenient to provide the pivotable tool head with devices for the feeding of bristles and staple wire in dependence upon the turning movement of the tool head, so as to cause an accurate amount of bristles and length of staple wire to be presented at the exact moment and point where the tuft is to be formed in order to be placed and secured in the hole just made in the brush stock at the other end position of the turning movement of the tool head.

Machines provided with arrangements in accordance with the present invention are conveniently so made that two or more tool heads are controlled by means of one common cam or curve disc, whereby the production capacity of the machine is considerably increased and the size of

the machine and mechanical equipment of the same may be reduced.

On the accompanying drawings a horizontal machine for the making of brushes, with arrangements in accordance with the present invention is schematically shown by way of example. Parts which are not essential for the understanding are omitted for the sake of simplicity of the drawings, the same being presumed to be familiar to those skilled in the art.

On the drawings:

Figure 1 shows the machine as seen from above.

Figures 2 and 3 show vertical sections through the machine, along the lines II—II and III—III in Figure 1, respectively, and

Figures 4 and 5 show the bristle feeding arrangement on a larger scale.

On the drawing, 1 designates the machine frame in which a horizontal, through shaft 2 is located and driven in any convenient manner, for instance through the medium of a pulley 3, through a clutch of any convenient type, for instance of the friction type which is not shown and which may be operated by the machine operator by means of a pedal extending along the whole length of the machine.

Two vertical shafts and one horizontal shaft are driven from the main shaft 2. The vertical shafts 4 and 5 are connected to the main shaft by means of bevel gears 6 and 7, respectively, and drive the crank arrangements of the two tool heads 8 and 9. In Figure 2 only the support of the tool head 8 is shown, whereas the head 9 is shown with a tool 10 for the drilling of holes in the brush stock, which is shown at 11 to the right in Figure 3, and a tufting tool 12 for the making of bristle tufts and staples and for the securing of the tufts in holes drilled in the brush stock 11. Further, each of the heads 8 and 9 is provided with a bristle passage 13 with a pressure member 14 as well as a device 15 for the feeding of wire for the production of staples. Each of these tools may be of any known type, for instance of the type described in the German patent specification No. 524,709.

A disc 16 is arranged on the shaft 2 between the gears 6 and 7 for the control of the movements of the tool heads and the spanner table for the brush stock. The disc 16 is made with one exterior curved groove 17 which, through the medium of a lever 18 and a connecting link 19 controls the turning movements of the tool heads, and a lateral groove 20 which, through the medium of the lever system 21 controls the double reciprocating movement of the spanner table 22.

The horizontal auxiliary shaft 23, which is connected to the shaft 2 through the gear 24 drives an eccentric disc 25, which in a manner known per se controls the movements of the template used for the locating of the individual

holes in the brush stock. This automatic template control may, however, be dispensed with and the template be carried along manually.

In the following description of the machine and the function of the same it is first assumed that the tool heads are standing in the position shown in Figures 1 and 4, wherein the placing and securing of a tuft is just finished in the brush stock 11 which is spanned on to a table which is not shown in the drawing, but is located perpendicularly to the plane of the paper in the Figures 1, 3, 4 and 5. Under the control of the curved groove 28 the table is moved backwards on the rack 22 perpendicularly to the tool 12 and by means of the eccentric disc 25 the template is moved on so as to cause the brush stock to be moved upwards or downwards and/or sideways to a position for the drilling of the next hole. At the same time the tool heads 8 and 9 are turned from the position shown in Figure 4 to that shown in Figure 5, wherein the drilling tool 10 is in working position. During this movement of the tool head the guide ruler 26 is moved together with the head in such a manner that the recess 27 enters into the bristle passage 13 and is filled with the bristle material which is subjected to a constant pressure by the spring actuated pressure member 14. During the last part of the movement the picker 28, which is pivotably mounted at 29 in the head 12 and which is pressed against this head by means of a spring 30, is turned against the action of this spring by the engagement of the fixed projection 31 on the picker with the nose 32 of the spring actuated holder member 33, so that the point 34 of the picker 28 will pass under the wall 35 of the bristle channel 36 and the projection 31 will fall into the recess 37 in the member 33.

In the position shown in Figure 5 the drilling tool 10 is in working position so that the same under the action of a cord drive over the pulley 38 will drill a new hole in the brush stock 11 when the stock carrying table is again swung inwardly. The tufting tool 12 is in position for reception of the bristle for one tuft which is lying ready in a recess 39 in the channel wall 35, and the conveyor device 15 has, by means of a spring which is actuated in dependence of the state of movement of the tool head, fed staple wire so that the correct length of wire is present in the tool 12 when the staple forming is to be performed by means of devices (not shown) driven by the shafts 4 and 5.

When the drilling of the new hole is made and the table is again swung outwardly, the tool heads are again swung to tuft forming position. At the beginning of this movement the projection 31 will engage the nose 32 and, in sliding upon the same, press the holder member 33 away from the channel wall 35 so that the point 34 may enter the recess 39 and carry along the bristle lying therein. During the continued movement, the recess 27 will feed the bristle into the channel 36 and place it in the recess 39, the holder member being momentarily pushed away by a pin 40 on the ruler 26 entering into engagement with or sliding along the sloping surface of a spring actuated pawl 41 on the holder member 33, to the effect that the bristle may pass by the projection 42 on the holder member and be placed in the recess 39, ready to be caught by

the picker 28 the next time the tool head is swung to drilling position. In the meantime the staple is formed in the tool 12 so as to be ready to be laid around the new tuft just fetched, whereupon the tuft making tool 12 performs its function when the brush stock is again carried against the tool by a new turning of the table on the rack 22.

What I claim as new and desire to protect by Letters Patent of the United States is:

1. In a brush making machine comprising devices for the drilling of bristle tuft receiving holes in a brush stock, devices for the formation of bristle tufts to be inserted into the said holes, devices for the cutting and feeding of staple wire to bind the said tufts in the said holes and devices for the placing of the said bristle tufts in the said holes and fixing the same by means of the said staple wire, said devices being combined into a tool head which is rotatably mounted on an axis, and means for moving said brush stock toward and away from said tool head in a path perpendicular to the said axis.

2. In a brush making machine comprising devices for the drilling of bristle tuft receiving holes in a brush stock, devices for the formation of bristle tufts to be inserted into the said holes, devices for the cutting and feeding of staple wire to bind the said tufts in the said holes and devices for the placing of the said bristle tufts in the said holes and fixing the same by means of the said staple wire, said devices being combined into a tool head which is rotatably mounted on an axis, and means for moving said brush stock toward and away from said tool head in a path perpendicular to the said axis, a cam disc being provided for the common control of the turning movement of the said tool head and the reciprocating movement of the said stock.

3. In a brush making machine comprising devices for the drilling of bristle tuft receiving holes in a brush stock, devices for the formation of bristle tufts to be inserted into the said holes, devices for the cutting and feeding of staple wire to bind the said tufts in the said holes and devices for the placing of the said bristle tufts in the said holes and fixing the same by means of the said staple wire, said devices being combined into a tool head which is rotatably mounted on an axis, and means for moving said brush stock toward and away from said tool head in a path perpendicular to the said axis, a cam disc being provided for the common control of the turning movement of the said tool head and the reciprocating movement of the said stock and means associated with the said tool head for feeding bristle material and staple wire in dependence upon the turning movement of the said tool head.
